UNITED STATES PATENT OFFICE.

GEORGE C. MOORE, OF WORCESTER, MASSACHUSETTS.

ELASTIC WEBBING.

1,082,963.

Specification of Letters Patent.

Patented Dec. 30, 1913.

Application filed August 18, 1911. Serial No. 964,351.

To all whom it may concern:

Be it known that I, George C. Moore, a citizen of the United States, residing at Worcester, in the county of Worcester, State of Massachusetts, have invented a certain new and useful Improvement in Elastic Fabric, of which the following is a specification, reference being had therein to the accompanying drawings.

The object of the invention is to provide an elastic webbing with inelastic sections of novel character, and to secure the rubber threads adjacent the said sections in such manner that when cut at such sections their cut ends will be securely fastened and prevented from becoming drawn into the intermediate portions of the fabric; and to make provision for finishing the goods by starching and calendering processes, or the like handling.

An embodiment of the invention is illustrated in the drawings, in which latter—

Figure 1 is an isometric view of a portion of fabric embodying the invention, showing several elastic and inelastic sections. Fig. 2 is an edge view of a portion of the fabric showing one of the inelastic sections with the intermediate ply severed.

Having reference to the drawings:—I weave a web having successive elastic sections σ , σ , σ , respectively of the required length. The web contains rubber warp threads to confer elasticity, as usual, and the fabric structure of the elastic sections may be of any approved weave.

I provide sewing sections of novel and improved character, by changing the weave at proper intervals, and thereby producing a short length of three-ply web, consisting of the upper ply p , composed of surface-warps interwoven with picks of weft or filling, the bottom ply p' similarly composed, and the intermediate ply p'' composed of the rubber threads and gut warp-threads interwoven with the weft or filling. I preferably unite the upper and bottom plies p , p' , by means of the weft or filling along one margin of the web or fabric, so as to produce a finished edge, which will result from causing the weft or filling to pass transversely through one of the said plies, then through the other thereof, then back through the latter, then through the first, and so on. The two plies referred to are left unconnected at the other margin of the web or fabric to give access to the intermediate ply. The latter is woven

unconnected with the upper and lower plies p , p' . The three-ply section is produced of a length sufficient for two sewing sections, in order that when, subsequent to the finishing, the fabric or web is severed into lengths by cutting across the sewing section, a portion of the latter may remain in connection with each length.

The disconnection of the plies p , p' , from each other along one edge of the fabric or web enables a pair of scissors or other cutting implement to be inserted between them, so that the intermediate ply p'' may be cut across without cutting the plies p , p' . The web fabric or web is left continuous, with the plies p , p' , of the respective sewing sections extended, flat and smooth, permitting the fabric or web to be starched and calendered or otherwise finished without difficulty by the ordinary methods and machinery employed in connection with elastic fabrics or webbing heretofore. If the said intermediate ply, containing rubber threads woven under tension were not cut, such ply would shrink and thereby cause the outer plies to ruffle or shrink, rendering it impracticable to starch and calender or otherwise finish the goods in that condition. The weaving of the rubber threads into the intermediate ply at the sewing section serves to fasten the cut ends of such threads when the said ply is severed, so as to prevent such ends from drawing back into the fabric or web. The two outer plies p , p' , lying one on top of the other constitute an inelastic portion which may be stitched or clamped to the garment or the like to which a given length of the fabric or web is attached for use.

When the intermediate ply p'' is cut across, the ends of the same contract in the manner indicated in Fig. 10. They will be inclosed between the two outer inelastic plies, so that they will not appear at the exterior of the inelastic section, and consequently they will not interfere with the finishing operations or affect the appearance of the webbing. When the web is divided into short lengths by cutting across the inelastic sections, and such lengths are attached to garments by stitches passing through the inelastic plies, the stitches will pass only through such plies, and consequently the needle will not penetrate or cut the rubber threads in the sewing operation. The short ends of the elastic intermediate ply will be hidden between the two inelastic plies. When a

clamp or other device is secured to one of the short lengths of webbing, it will be made fast to the two inelastic plies of an inelastic section. Inasmuch as the said intermediate 5 ply is somewhat loosely woven, the end portions of the rubber threads will be free to swell or expand as they shorten in length. This will insure against their drawing into and through the more closely woven elastic 10 sections. These portions of the rubber threads will remain more or less loosely held by the weft or filling which is interwoven with the rubber threads and with the gut threads to form the elastic intermediate ply.

What is claimed as the invention is:—

1. An elastic web woven in alternate elastic sections and intermediate sections, each intermediate section in three separate plies, namely upper and lower inelastic plies and

an intervening ply in which the rubber 20 threads are bound by being interwoven with weft-threads and thereby prevented from drawing into the adjoining elastic sections after such intervening ply is cut.

2. An elastic web woven in alternate elastic sections and intermediate sections, each intermediate section in three separate plies, namely upper and lower inelastic plies connected to each other along one margin of such section, and a loose intervening ply in 25 30 which the rubber threads are interwoven with weft-threads.

In testimony whereof I affix my signature in presence of two witnesses.

GEORGE C. MOORE.
